US00D756995S

(12) **United States Design Patent**
Yamazaki et al.

(10) **Patent No.:** **US D756,995 S**
(45) **Date of Patent:** **** May 24, 2016**

(54) **PORTABLE INFORMATION TERMINAL**

(71) Applicant: **SEMICONDUCTOR ENERGY LABORATORY CO., LTD.**, Atsugi-shi, Kanagawa-ken (JP)

(72) Inventors: **Shunpei Yamazaki**, Tokyo (JP); **Yoshiharu Hirakata**, Kanagawa (JP)

(73) Assignee: **SEMICONDUCTOR ENERGY LABORATORY CO., LTD.**, Kanagawa-ken (JP)

(**) Term: **14 Years**

(21) Appl. No.: **29/487,590**

(22) Filed: **Apr. 10, 2014**

(30) **Foreign Application Priority Data**

Oct. 18, 2013 (JP) 2013-024250

(51) **LOC (10) Cl.** **14-02**

(52) **U.S. Cl.**

USPC **D14/341**

(58) **Field of Classification Search**

(57) **CLAIM**

We claim, the ornamental design for a portable information terminal, as shown and described.

DESCRIPTION

FIG. 1 is a front view of a portable information terminal showing our new design;

FIG. 2 is a rear view thereof;

FIG. 3 is a right side view thereof;

FIG. 4 is a left side view thereof;

FIG. 5 is a top plan view thereof;

FIG. 6 is a bottom plan view thereof;

FIG. 7 is a front perspective view thereof; and,

FIG. 8 is a rear perspective view thereof.

1 Claim, 4 Drawing Sheets
